WEB WINDING

Oscar C. Roesen, Scarsdale, N. Y., assignor to
 Wood Newspaper Machinery Corporation,
 Plainfield, N. J., a corporation of Virginia

Application May 19, 1943, Serial No. 487,585

15 Claims. (Cl. 242—56)

This invention relates to web roll winding and more particularly concerns an improved method and apparatus for winding a continuously running web into successive rolls for subsequent use as such or in web consuming apparatus.

Large web rolls are customarily wound from the web issuing from a paper or other web making machine, or from a web drawn from a master roll. To expedite this operation, it is necessary that when a given roll is completely wound, the continuous web running to it be severed and the severed end started around a core to wind another roll, and this should be accomplished without stopping or materially retarding the movement of the web.

In accordance with the present invention, it is proposed to provide an improved method for winding a continuously moving flexible web, such as the paper web running from a paper making machine, into a succession of web rolls and to provide improved apparatus for performing this method. In particular, it is the object of the invention to provide a method and apparatus by means of which the moving web running to a roll being wound may be severed and the severed end thereof started around a roll core to start the winding of another roll without stopping or retarding the speed of travel of the web and without leaving a tail or backfold at the point where the web is started on the new roll core. Another particular object of the invention is to provide a method and apparatus of the type described in which the operations of severing the web and starting its end around a new roll core are governed by control actuators carried by the web itself, and in which improved means are provided for applying control actuators and adhesive layers in properly spaced relation on the web as it travels to the roll winding apparatus. Various additional objects and advantages of the invention will be apparent as the description of certain embodiments thereof progresses.

In describing the invention in detail, reference will be made to the accompanying drawings, in which certain embodiments thereof have been illustrated. In the drawings:

Fig. 1 is a diagrammatic and simplified elevation of web winding apparatus embodying my invention and capable of carrying out my method;

Fig. 2 is a perspective view of a roll core used in the apparatus of Fig. 1;

Fig. 3 is a sectional view of the roll core shown in Fig. 2;

Fig. 4 is an enlarged plan view of a section of the web employed in the apparatus of Fig. 1;

Fig. 5 is a diagrammatic sectional view illustrating a scanning device of the type shown in Fig. 1;

Fig. 6 is a partial elevation of the apparatus of Fig. 1, showing a modified form of web-carried control actuators and control actuator responsive devices;

Fig. 7 is a diagrammatic and simplified elevation of a modified form of my improved roll winding apparatus; and

Fig. 8 is an enlarged plan view of a section of web used in the apparatus of Fig. 7.

Referring particularly to Fig. 1, the web roll winding apparatus there illustrated is supplied with a web 9 of paper or other relatively thin flexible material. The web 9 may be derived from any desired source, such as a master roll 10, or it may issue directly from the drier section 11 and calender 12 of a paper making machine. The web 9 travels over guide rollers 13, 14, 15 and 16 and to the winding mechanism generally designated M, where it is wound into rolls.

The winding mechanism includes a reel including a stand 17 and a reel shaft 18 carrying two end spiders each having three roll arms 19, 20 and 21. Since the roll is shown in elevation, the arms of one spider only are shown. The roll arms 19, 20 and 21, respectively, carry roll spindles 22, 23 and 24 for carrying the cores of the web rolls being wound thereon. The spindles 22 carry a new core 25 in what will be termed the core replacement position, the spindles 23 carry a roll 26 being wound, and the spindles 24 carry a completely wound roll 27 which is in position to be removed and replaced by a new core.

A set of tensioned driving belts 28 is disposed adjacent the reel. Three or more such belts may be used as illustrated in Fig. 4. The belts 28 run in contact with the cylindrical surfaces of the core 25 and the roll 26, the web running to the roll 26 lying between the belts and the core 25. The belts 28 pass over the idler rollers 29, 30 and 31, a weighted tension roller 32 and a driving roller 33. The belts 28 are spaced apart in accordance with conventional practice sufficiently to permit movement of web severing means therebetween. The driving roller 33 is driven at a speed such that the belts move at or very slightly faster than the speed at which the web 9 is delivered from the paper making machine or other source. I have illustrated a

driving motor 34 which may be connected by a shaft 35 and suitable gearing 36 and 49 to simultaneously drive the roller 33 and the calender 12.

Each arm of the reel is provided with a set of web starting belts, designated 37, 38 and 39 for the respective arms 19, 20 and 21. Each of these comprises a series of parallel belts spaced apart axially of the web roll and carried by a set of triangularly arranged idler rollers. Referring to the belts 37, the rollers 40, 41 and 42 are journaled in a frame 43 that is slidably mounted to move longitudinally of the arms 19 as by engagement of a suitable stud on the frame in slots 44 in the arms. The rollers 41 and 42 are carried in spring pressed journals as shown so that when the belts 37 contact the cylindrical surface of the core 25, the rollers 41 and 42 retract and permit the belts to contact the core surface over a considerable arc. The starting belts 38 and 39 on the arms 20 and 21 that are disposed in positions other than the core replacement position are retracted as shown so that they do not contact the rolls 26 and 27 carried by these arms. This may be accomplished by sliding the frames 43 carrying these belts back toward the reel axis where they may be held by any suitable means.

Suitable control actuator responsive devices are provided for governing the operation of severing the web and starting the severed end thereof around a new core in response to web-carried control actuators. These devices may take the form of photoelectric scanners or electrical contacts. The photoelectric scanners are designated as a whole as D and D' and, as illustrated in Fig. 5, may include a housing 45 containing a light source 46, the light from which is columnated by a lens 47 and projected through a window 48 onto the web 9. The part of this light beam that is specularly reflected from the web enters another window 50 and acts on a photoelectric cell 51. A relay 52 is energized and so opens its contacts 53 so long as a predetermined amount of reflected light acts on the photoelectric cell 51. When the intensity of the reflected light is materially reduced, as by movement of a control actuator comprising a black or dark area 54 on the web 9 past the scanning device, the relay 52 is de-energized and its contacts 53 close. The scanning device may include an amplifier A for the photoelectric cell current and other known refinements, illustration of which is not necessary to an understanding of the present invention.

In the embodiment of Fig. 1, one scanning device D of the type described is disposed adjacent the outer surface of the web 9 at a point just beyond that where the web contacts the roll core 25 in the core replacement position, and a second scanning device D' is disposed adjacent the cylindrical surface of the core 25 at a point remote from its area of contact with the web 9. The device D' is disposed to direct its light beam to one side of the starting belts 37, and the device D similarly directs its light beam directly onto the web 9 at some point where it is not covered by one of the driving belts 28. The devices D and D' may be carried by any suitable means which may comprise arms permitting movement of these devices out of the path of the reel-carried rolls when the reel is rotated. Various forms of pivoted frames for this purpose are known, and some such forms are illustrated in my co-pending applications, Serial No. 483,045, filed April 14, 1943, entitled "Web splicing," and

Serial No. 426,557, filed January 13, 1942, entitled "Web roll replacement," now Patent No. 2,320,657, dated June 1, 1943.

A cutting device K is suitably supported adjacent the outer surface of the web 9 just beyond the area thereof that contacts the roll core 25 in the replacement position. This device includes a blade 67 extending transversely across the web 9 and suitably sub-divided to pass between the belts 28. The blade 67 is carried by a plunger 68 slidably disposed in a housing 70 and biased toward its extended position by a spring 71. The blade 67 is held in its retracted position against the bias of the spring 71 by a spring pressed latch 72 engaging a notch in the plunger, as shown, and a solenoid 73 is provided for retracting the latch 72 when energized and so permitting the spring 71 to extend the blade 67. When extended, the blade 67 severs the web 9 and carries the free end thereof into the nip between the starting belts 37 and the roll core 25. If desired, a ledge or flange 74 may be provided adjacent the cutting edge of the blade 67 to assist in carrying the severed end of the web into the belt nip. The solenoid 73 is connected to a source of energy indicated at 75 through a circuit including the relay contacts of the scanning devices D and D' in series, so that the blade 67 is extended only when control actuators are opposite both of the scanning devices. A handle 69 may be provided on the blade plunger 68 for retracting the same to its latched position after each web severing operation.

In accordance with the present invention, a control actuator and a layer of special adhesive are simultaneously applied to certain areas of the web 9 running to the winding mechanism M. This is accomplished by adhesive applying and printing mechanisms that are relatively spaced longitudinally along the path of web travel at any convenient point. As shown, a spray nozzle 55 connected to an adhesive reservoir 49 is disposed to spray a layer of adhesive on the surface of the web 9 that later contacts the roll core 25. The nozzle is actuated when air under pressure is supplied thereto by opening of the valve 56. The nozzle 55 extends laterally across the entire width of the web 9 so that adhesive is applied to the entire surface of the passing web except for a strip thereof adjacent one edge, which is protected by a shield 57.

A control actuator which may comprise a stripe of black or dark ink or other air-drying dye or pigment is applied to a surface of the web 9 by a printing roller 58 when the web is pressed against this roller by an impression roller 59. The roller 58 is supplied with ink or the like from a reservoir 68 by a roller 89. The control actuator may be applied to the under surface of the web as shown or to the upper surface thereof. The printing roller 58 is slightly narrower than the shield 57 and is aligned with it, so that the control actuator 54 extends along the bare strip of web running through the adhesive coated area 61, as shown in Fig. 4. The impression roller 59 is depressed by the energization of a solenoid 62, the air valve 56 is opened by energization of a solenoid 63, and a push button switch 64 is arranged to simultaneously energize the solenoids 62 and 63 from a suitable source of energy indicated by the terminals 65. Since simultaneous energization of these solenoids initiates application of both the adhesive and the control actuator, and since the actuator printing device is spaced ahead of the adhesive spray nozzle in the

direction of web travel, the control actuator 54 leads the adhesive bearing area 61 by a predetermined interval. This interval is made equal to the distance between the area where the web 9 engages the roll core 25 and the point where the light beam from the scanning device D' strikes the web. The control actuator 54 and adhesive area 61 each extend longitudinally of the web 9 for a distance at least equal to the maximum circumference of the new roll core. This may be accomplished by holding the push button 64 closed for a suitable interval, either manually or by timing means responsive to the linear travel of the web 9. The control actuator 54 and adhesive coating 61 may be dried on the web by any suitable means such as a heating chamber 66 through which the web passes.

The adhesive comprising the layer 61, which will be hereinafter referred to as a self-sticking adhesive, is of the nature of a rubber cement. Adhesives of this type are described in detail in my co-pending application Serial No. 403,515, filed July 22, 1941, entitled "Web roll changing," now Patent No. 2,320,656. As there explained, this self-sticking adhesive has the properties of adhering tenaciously to the paper or other web when applied thereto in liquid form, but when dried does not adhere to an uncoated web surface. The dried self-sticking adhesive coatings cohere tenaciously with similar applied and dried coatings.

When the web rolls being wound are to be used in the web roll changing method described and claimed in my aforesaid co-pending application Serial No. 403,515, the core end of the web on each roll carries a layer of the above described self-sticking adhesive on its inner surface. As explained in said application, this core end of the web may conveniently comprise a separate sheet or web section to which the inner end of the web on the roll is spliced. A web roll of this type is illustrated in the embodiment of Figs. 1 through 6. Accordingly, the new core 25 carries a sheet or web section 76 bearing a coating of self-sticking adhesive 71 on its inner surface. The outer end of the sheet 76 is secured to the underlying layer by suitable separable means such as the centrally perforated frangible gummed tabs 78 which are of known construction and are described in detail in United States Letters Patent No. 1,996,497. The outer surface of the sheet 76 carries a layer 79 of applied and dried self-sticking adhesive on its leading end as shown in Figs. 2 and 3. A control actuator comprising a black or dark colored area 80 is provided on the outer surface of the sheet 76 at a point so spaced from the adhesive layer 79 that the actuator 80 comes opposite the scanning device D' when the adhesive layer 79 is in contact with the web 9 as shown in Fig. 1. The control actuator 80 is disposed at such a position that it is not obscured by the starting belts 37.

In operating the above described embodiment of the invention, before the roll 26 being wound has reached the desired size, a roll core 25 bearing a core end sheet as described above is mounted on the spindles 22 and moved to the core replacement position as shown, the starting belts 37 being moved into contact with the core. Contact between the core and the web 9 accelerates the core until its peripheral velocity equals or approximates web speed. Thereafter, when the roll 26 reaches the desired size, the operator closes the push button switch 64 for a suitable interval and so applies a control actuator 54 and an adhesive

layer 61 to the web 9 running to the winding mechanism, as explained above.

Before the adhesive layer 61 reaches the core 25, the layer 79 at the leading end of the sheet 76 on the core 25 repeatedly contacts the web 9, but due to the explained properties of the self-sticking adhesive, this layer does not adhere to the web. When, or just after, the leading edge of the adhesive layer 61 comes into contact with the sheet 76 on the core 25, the control actuator 60 moves in front of the device D and closes its relay contacts. Thereafter, as soon as the control actuator 80 on the sheet 76 moves in front of the scanning device D', indicating that the self-sticking adhesive layer 79 is in contact with the web 9, the relay contacts of the device D' close, completing the energizing circuit for the solenoid 73 and so releasing the blade 67. The blade 67 severs the web 9 just beyond the point where it leaves the core 25 and pushes the severed end of the web into the nip between the starting belts 37 and the core. At the same time, contact between the self-sticking adhesive layers 61 and 79 splices the web 9 to the end of the sheet 76 on the core. The starting belts 37 hold the leading end of the web 9 onto the core surface and the web 9 is smoothly wound on the core as it rotates. The combined action of the severing blade and the starting belts prevents the formation of any appreciable trailing tail or backfold of the leading end of the web. When the web is well started on the new core, the reel may be turned counterclockwise to increase the wrap of the driving belts 28 about its cylindrical surface and the winding of the roll proceeds without further attention until the new roll is substantially completed, whereupon the described core replacement operation is repeated.

It is not essential that photoelectric scanning devices be employed, and various other means responsive to the position of control actuators on the surface of the running web and new core may be employed. For example, as illustrated in Fig. 6, the control actuators 54' and 80', which correspond in location to the actuators 54 and 80 of Fig. 1, may comprise electrically conductive layers such as stripes of metallic paint or lacquer, applied strips of metal foil, or other conductive coatings. When such conductive control actuators are used, the responsive means may take the form of a pair of electrically conductive brushes mounted adjacent each other and in contact with the web or other surface carrying the control actuator.

As shown in Fig. 6, a pair of brushes 81 is mounted adjacent and in contact with the running web 9' and a similar pair of brushes 82 is mounted adjacent and in contact with the core 25', the brushes 81 being aligned with the control actuator 54' on the web 9' and the brushes 82 being aligned with the control actuator 80'. The operation is the same as that described above in connection with the arrangement of Fig. 1; the blade 67 being released when both sets of brushes 81 and 82 are electrically connected by the respective control actuators 54' and 80'. The actuator 54' may be applied to the moving web in the form of an air-drying paint or lacquer by the mechanism disclosed in Fig. 1 or its equivalent, and the spaced relation of the control actuators 54' and 80' with respect to the self-sticking adhesive bearing areas 61' and 79' is the same as that described in connection with the correspondingly numbered elements illustrated in Fig. 1.

The method and apparatus of the present invention is admirably adapted to the winding of

continuously moving flexible webs into rolls having no core end strip or section carrying an adhesive layer. Apparatus for winding such web rolls is diagrammatically illustrated in Figs. 7 and 8. In general, this apparatus is the same as that previously described in connection with Fig. 1 but somewhat simplified, and accordingly the parts shown in Figs. 7 and 8 correspond to those described in connection with Fig. 1 and are designated by like reference characters with distinctive exponents.

The roll core 25" employed in the modification of Fig. 7 carries a layer or coating 83 of applied and dried self-sticking adhesive covering its entire cylindrical surface. Control actuator responsive brushes 84 or equivalent means are disposed adjacent the web 9" just above the point where it leaves the surface of the core 25", and these brushes cooperate with the control actuator 85 to close a circuit for energizing the electromagnet 13' and so to release the blade 67', sever the web 9" and push the severed end thereof into the nip formed by the starting belts 37'. The control actuator 85 is an electrically conductive strip, and it leads the self-sticking adhesive coating 86 by an interval equal to the distance between the point where the web 9" contacts the roll core 25" and the point where it contacts the brushes 84. The self-sticking adhesive coating 86 is applied by a nozzle 55' from a reservoir 49' under control of a valve 58' operated by a solenoid 63'. A suitable conductive coating such as aluminum paint may be applied to form the control actuator 85 by the printing roller 58' when the impression roller 59' is depressed by the solenoid 62', the paint being supplied from the reservoir 88' by the roller 89'. The distance between the nozzle 55' and the printing cylinder 58' is equal to the above noted desired interval between the control actuator 85 and the self-sticking adhesive coating 86.

In operating the apparatus illustrated in Figs. 7 and 8 in accordance with my improved method, the operator merely closes the push button switch 64' when a new roll is to be started. The interval during which the switch 64' is closed need not be as long as in the above described operation of the apparatus of Fig. 1, because the self-sticking adhesive layer 86 need be only long enough to make a secure splice. Thus the trailing end of the control actuator 85 generally stops short of the self-sticking adhesive layer 86, as shown in Fig. 8. The actuator 85 and layer 86 may be dried as the web 9" passes through the heated chamber 66'. When the actuator 86 connects the brushes 84, the blade 67' is released, the web is severed and the severed end thereof wrapped around the core 25 and tucked into the nip under the starting belts 37'. At the same time, the web 9" is spliced to the core 25" by engagement between the self-sticking adhesive layer 86 on the web and the similar layer 83 on the core surface.

I claim:

1. In a method of transferring a moving flexible web running to a web roll being wound to a core to start the winding of another web roll in which the web running to the roll being wound travels in contact with the core surface and adhesive is applied to the running web to stick it to the core, the improvement which comprises applying a control actuator to the web adjacent the adhesive thereon and controlling the severing of the running web between the core and the roll being wound by movement of such web-car-

ried control actuator past a point such that the adhesive is in contact with the core surface.

2. The method of transferring a moving flexible web running to a web roll being wound to a core to start the winding of another web roll which comprises bringing the web running to the roll being wound into contact with the surface of a core, applying a layer of adhesive to the web moving toward the core, applying a control actuator to the web adjacent the adhesive layer and severing the web between the core and the roll being wound in response to movement of the control actuator past a fixed point adjacent the core.

3. The method of transferring a moving flexible web running to a web roll being wound to a core to start the winding of another web roll which comprises bringing the web running to the roll being wound into contact with the surface of a rotatable core, bringing a moving belt into contact with the surface of said core not engaged by the web, applying a control actuator to the moving web approaching the core and, in response to movement of the control actuator past a fixed point, severing the web between the core and the roll being wound and tucking the severed end thereof between the belt and the core surface.

4. The method of transferring a moving flexible web running to a web roll being wound to a core to start the winding of another web roll which comprises bringing the web running to the roll being wound into contact with the surface of a rotatable core, bringing a movable belt into contact with the core surface not engaged by the web, applying a layer of adhesive and a control actuator to the moving web approaching the core, severing the web between the core and the roll being wound and tucking the severed end thereof between the belt and the core when the adhesive layer contacts the core, and controlling the web severing and tucking operation by movement of the control actuator on the web past a fixed point.

5. The method of transferring a moving flexible web running to a web roll being wound to a core to start the winding of another web roll which comprises bringing the web running to the roll being wound into contact with the surface of a rotatable core, simultaneously applying adhesive and a control actuator to the web approaching the core from points spaced along the path of travel of the web, cutting the web when the adhesive layer thereon is in contact with the surface of the core and controlling the cutting operation by movement of the control actuator past a fixed point adjacent the core.

6. The method of transferring a moving flexible web running to a web roll being wound to a core to start the winding of another web roll which comprises bringing the web running to the roll being wound into contact with the cylindrical surface of a rotatable core having a layer of self-sticking adhesive and a control actuator spaced therefrom on its cylindrical surface, simultaneously applying a self-sticking adhesive layer and a control actuator to the web approaching the core, cutting the web when the adhesive layer thereon is in contact with the adhesive layer on the core and controlling the cutting operation by movement of the control actuators on the core and on the web past fixed points.

7. Apparatus for transferring a moving flexible web running to a roll being wound to a core to start the winding of a new roll comprising means for rotatably supporting a roll core in contact with a moving web, means for applying a control actuator to the web approaching said

core and means responsive to movement of said control actuator past a fixed point along the path of travel of the web for severing the web beyond the core and starting the severed end thereof around the core.

8. Apparatus for transferring a moving flexible web running to a roll being wound to a core to start the winding of a new roll comprising means for rotatably supporting a roll core in contact with a moving web, means for applying a control actuator and a layer of adhesive to the web approaching said core and means responsive to movement of said control actuator past a fixed point such that the adhesive layer is in contact with the core for severing the web beyond the core.

9. Apparatus for transferring a moving flexible web running to a roll being wound to a core to start the winding of a new roll comprising a roll core having a layer of self-sticking adhesive and a control actuator at circumferentially spaced points on its cylindrical surface, means for rotatably mounting said roll core with its cylindrical surface in contact with a web running to a roll being wound, means for applying a layer of self-sticking adhesive and a control actuator to the moving web approaching said core, and means responsive to movement of said control actuators past fixed points such that the two self-sticking adhesive layers are in contact for severing the web beyond the core.

10. Apparatus for transferring a moving flexible web running to a roll being wound to a core to start the winding of a new roll comprising means for rotatably mounting a roll core with its cylindrical surface in contact with a web running to a roll being wound, a movable belt engaging the cylindrical surface of said core over the area thereof not engaged by the web, and a blade adjacent the path of the web beyond the core for severing the web and tucking the severed end thereof between the cylindrical surface of the core and the belt.

11. Apparatus for transferring a moving flexible web running to a roll being wound to a core to start the winding of a new roll comprising a roll core having a layer of self-sticking adhesive covering its cylindrical surface, means for rotatably mounting said core with its cylindrical surface in contact with a web running to a roll being wound, means for applying a layer of self-sticking adhesive to the surface of the web approaching said core and means responsive to the movement of a distinctively marked section of said web for severing said web beyond the core when said web-carried adhesive layer moves into contact with the cylindrical surface of said core.

12. Apparatus for transferring a moving flexible web running to a roll being wound to a core to start the winding of a new roll comprising means for applying a layer of self-sticking adhesive and a control actuator to the surface of the web approaching said core, web severing means adjacent the path of the web leaving said core and means responsive to the movement of said control actuator past a point such that the web-carried adhesive layer is in contact with the

core surface for operating said web severing means.

13. Apparatus for transferring a moving flexible web running to a roll being wound to a core to start the winding of a new roll comprising a roll core having a layer of self-sticking adhesive covering its cylindrical surface, means for rotatably mounting said core with its cylindrical surface in contact with a web running to a roll being wound, a movable belt engaging the cylindrical surface of said core over an area thereof not engaged by said web, a blade adjacent the path of the web beyond the core acting when released to sever the web and tuck the severed end thereof between the core surface and said belt, means for applying a layer of self-sticking adhesive to the surface of the web approaching said core and means responsive to movement of a distinctively marked section of said web for releasing said blade when said web-carried adhesive layer moves into contact with the core surface.

14. Apparatus for transferring a moving flexible web running to a roll being wound to a core to start the winding of a new roll comprising a roll core having a layer of self-sticking adhesive and a control actuator at circumferentially spaced points on its cylindrical surface, means for rotatably mounting said core with its cylindrical surface in contact with a web running to a roll being wound, means for applying a layer of self-sticking adhesive and a control actuator to the moving web approaching said core, a movable belt engaging the cylindrical surface of said core over an area thereof not engaged by said web, releasable means adjacent the path of the web leaving said core for severing the web and tucking the severed end thereof between said core and said belt when released, and means responsive to movement of said control actuators past points such that the self-sticking adhesive layers on said core and said web are in contact for releasing said releasable means.

15. Apparatus for transferring a moving flexible web running to a roll being wound to a core to start the winding of a new roll comprising a roll core having a layer of self-sticking adhesive and a control actuator at circumferentially spaced points on its cylindrical surface, means for rotatably mounting said core with its cylindrical surface in contact with a web running to a roll being wound, means for applying a layer of self-sticking adhesive and a control actuator to the moving web approaching said core, a movable belt engaging the cylindrical surface of said core over an area thereof not engaged by said web, a blade adjacent the path of the web leaving said core for severing the web and tucking the severed end thereof into the nip between the core surface and said belt when said blade is operated, stationary devices located respectively adjacent the surface of said roll core and the surface of the web and operable upon passage of a control actuator, and means responsive to the simultaneous operation of said stationary devices for actuating said blade.

OSCAR C. ROESEN.
